[57] CLAIM

The ornamental design for a stand for exhibiting articles, as shown and described.

DESCRIPTION

FIG. 1 is a top plan view of a stand for exhibiting articles showing my invention;

FIG. 2 is a bottom view thereof;

FIG. 3 is a front view thereof;

FIG. 4 is a rear view thereof;

FIG. 5 is a left side elevation view thereof, the right side being a mirror image;

FIG. 6 is a sectional view taken along the line A—A of FIG. 3;

FIG. 7 is a right side perspective view showing my stand in reduced scale, with an article on display shown in broken lines for illustrative purposes only and forming no part of the claimed design;

FIG. 8 is a right side perspective view showing my stand in reduced scale, with a different article on display shown in broken lines for illustrative purposes only and forming no part of the claimed design;

FIG. 9 is a top plan view of the leg of my stand, shown in exploded view for ease of illustration;

FIG. 10 is a left side elevation view thereof, the right side being a mirror image;

FIG. 11 is a front view thereof;

FIG. 12 is a bottom plan view thereof;

FIG. 13 is a bottom plan view of the support body for my stand, shown in exploded view for ease of illustration;

FIG. 14 is a top plan view thereof;

FIG. 15 is a rear view thereof;

FIG. 16 is a front view thereof;

FIG. 17 is a left side elevation view thereof; and,

FIG. 18 is a right side elevation view thereof.
